CLAIM

The ornamental design for a vehicle hood vent, as shown and described.

DESCRIPTION

FIG. 1 is a front left top perspective view of a vehicle hood vent according to the present invention.

FIG. 2 is a front left perspective view of the hood vent shown in FIG. 1.

FIG. 3 is a rear right top perspective view thereof.

FIG. 4 is a rear right perspective view thereof.

FIG. 5 is a front view thereof.

FIG. 6 is a rear view thereof.

FIG. 7 is a left side view thereof.

FIG. 8 is a right side view thereof.

FIG. 9 is a top view thereof.

FIG. 10 is a bottom view thereof; and,

FIG. 11 is another top view of the vehicle hood vent shown in FIGS. 1-10, but mounted on a vehicle, and with the rest of the vehicle shown in broken lines which form no part of the claimed design but which are instead included to show environmental structure.

1 Claim, 10 Drawing Sheets
